UNITED STATES PATENT OFFICE

SAMUEL KOCH, OF BROOKLYN, NEW YORK,
POSITION BRAKE FOR SEWING MACHINES.

Application filed April 4, 1928. Serial No. 267,190.

This invention relates to a new and useful device in the nature of a position brake for sewing machines especially for stopping a sewing machine at any desired time and with the needle at any predetermined position.

An object of the invention is to provide a position brake for sewing machines comprising an engaging member adapted to engage a shoe as a means of stopping a sewing machine at any desired time when the needle of the sewing machine is in a raised position free from the cloth or material being sewn, so as to permit the ready removal of the said cloth, or by changing the location of the device, to stop the machine when the needle is in an engaged position in the said cloth, so as to permit the cloth to be readily shifted or angularly turned as is required when sewing garments, clothing or the like.

20 A further object of the invention is to provide a device of the class described, of novel construction and arrangement of parts hereinafter more fully described, claimed and illustrated in the accompanying drawing.

25. Fig. 1 is a front elevational view of a sewing machine having the invention applied thereto.

Fig. 2 is a side elevational view of the sewing machine hand wheel showing the shoe as embodied in my improved device secured thereto.

Fig. 3 is an end view thereof.

Fig. 4 is a front elevational detail view of the shoe as embodied in my improved device.

Fig. 5 is a top plan view thereof.

Fig. 6 is a vertical sectional view taken on the line 6-6 of Fig. 4.

Fig. 7 is a front elevational view of the shoe retainer as embodied in my improved device.

Fig. 8 is a top plan view thereof.

Fig. 9 is a fragmentary enlarged fractional view, taken on the line 9-9 of Fig. 1. In Fig. 1 of the accompanying drawing, I

is shown in Fig. 1 of the accompanying paper.

have shown a sewing machine 10 on table 11 and a power shaft 12 is rotatively mounted and provided with a wheel 13 connected by belt 15 to a clutch section 16 provided with a complementary clutch section 19, said clutch sections being supported by a bracket 18 depending from table 11. A flexible member 20 is extended over the section 19 and over the pulley 21 secured to the spindle 22 of the sewing machine 10.

The above described construction is such as will permit the sewing machines to be operated or driven. It is understood that the above mentioned shaft 12 is operatively connected to prime mover preferably an electric motor, not shown in the accompanying drawing.

Treddle 23 is pivotally mounted on the brackets 24 and 25 secured to the floor 26 directly below the sewing machine 10. A lever 27 is intermediately hinged as at 28 to the bracket 29 secured to the table 11. The lever 27 is provided with a free extremity 30 normally held in engagement with the section 19 by a tension spring 31 secured to the lever 27 and to the table 11. The flexible member 32 is secured to the extremity 33 of the lever 27 opposite the above mentioned free extremity 30 of the said lever and is secured to the free edge of the treddle 23. The lever 27 has an arm 25 engageable against section 16 for forcing the clutch sections together into operative positions.

The above described construction is such as will normally hold the sewing machine 10 in an operative position, until the treddle 23 is forced downwardly by the foot of the operator. 80

The foregoing description is symbolic of the usual power driven sewing machine such as generally employed in factories and the like. 85

As here embodied my improved device comprises an arm 35 secured to and horizontally disposed from the above mentioned 90

treddle 23. A rod 36 is pivotally secured as at 37 to the extended extremity of the arm 35 and similarly secured as at 38 to the lever 39 pivotally secured as at 40 to a bracket 41 attached to the table 10. An engaging rod 42 is pivotally secured as at 43 intermediately to the lever 39 at its lower extremity, and is extended vertically therefrom through an aperture 44 formed in the table 10 and is slidably mounted in the extended elements 45 and 46 of a bracket 47 secured to the table 10. The engaging rod 42 is provided with a horizontally extended portion 48 having a vertically extended free extremity 49. An expansion spring 50 is positioned or wound co-axial on the main portion of the engaging rod 42 intermediate the element 45 of the bracket 47 and the collar 51 secured to the engaging rod 43, as a means of normally holding the free extremity 49 of engaging rod 42 in engagement with the shoe 52.

The above mentioned shoe 52 is substantially of segment or arc shape construction and has formed therein apertures 53 and 54 adapted to receive the threaded members 55 and 56 respectively, bolts, screws or the like adapted to engage in apertures 57 and 58 formed in the retainer 59, of similar segment shape construction, as a means of attaching the shoe 52 to the hand wheel 60 of the sewing machine. It is understood that the shoe 52 may be attached to the hand wheel 60 at any desired portion thereof for the purpose as hereinafter set forth. As is customary in sewing machines the hand wheel 60 may be turned freely by loosening the end of the spindle 22.

The shoe 52 is provided with a tapered surface 61, tapered relative to the rear side of the shoe, and with a tapered surface 65 relative to the end edge of the shoe, the surface 65 being arranged to meet surface 61, and the shoe 52 has secured thereto as at 62 by bolts, screws or the like, a stop member 63 preferably of comparatively lightly compressed felt, positioned adjacent to the outermost portion of the tapered surface 61. Sunk-in from the surface 61 is a groove 66.

The above described construction is such as will permit the free extremity 49 of the engaging rod 42 to first engage the tapered surface 61 or 65 of the stop 52, when the treadle 23 is released by the foot of the operator and allowed to move upwards, and which will permit the engaging rod 42 to next engage the stop 63 and rest in groove 66 as a means of providing a stop for the purpose of stopping the sewing machine. It is understood that the shoe 52 may be attached to the hand wheel 60 and relatively positioned thereon or the relative position of the wheel 60 on the spindle 22 adjusted as a means of stopping the sewing machine so as to position the needle of the sewing machine in cloth being sewn or

disengaged with the said cloth for the purpose as above set forth.

Attention is directed that extremity 49 is bent outwards by the tapered surfaces 61 or 65 which acts to stop the wheel 60. Of course the wheel does not come to a complete stop until 49 strikes stop 63 and falls into groove 66. The brake 27 is so arranged as to merely slow down section 19 when applied to aid extremity 49 to properly stop the wheel 60.

It is to be understood that when it is intended to use my position brake device, an abutting lever 68 pivoted at 69 on bracket 70, is swung in an engaging position as shown in Fig. 1 of the drawings. This lever stops treadle 23 before the latter completes its final upward motion, thereby preventing brake lever 27 from touching section 19 and allowing the sewing machine to be stopped by the engaging rod 42.

In case it is desired to place my position brake into inoperative position, the abutting lever 68 is swung away from the treadle 23 and the hooked extremity 71 of a slide bar 72 is pulled outwardly. Slide bar 72 is secured to the bottom of table 11 by strap 73 and is provided with a tapered projection 74 which is adapted to engage the lever 39. When the slide bar 71 is pulled outwardly, lever 39 is rocked and the free extremity 49 of bar 42 is depressed below the shoe 52.

In operation of the sewing machine, the treadle 23 is pressed down for moving arm 35, rod 36 and extremity 49 down so as to permit rotation of wheel 60, and for moving member 32 down for pivoting arm 27 about 28 so as to press clutch sections 16 and 19 together transmitting rotation to the sewing machine. Upon upward motion of the treadle 23 clutch sections 16 and 19 disengage and extremity 49 moves upwards for stopping wheel 60 and the sewing machine.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention what I claim as new and desire to secure by United States Letters Patent is:

1. In combination with the hand wheel of a sewing machine, an arcuate shoe arranged for attachment on the hand wheel and formed with an outward tapered surface sloping outwards from the front to the rear, a bottom tapered surface sloping outwards from the bottom up and meeting said tapered surface, a vertical groove to the rear of the tapered surfaces, and a stop member attached on the shoe to the rear of the vertical groove.

2. In combination with the hand wheel of a sewing machine, an arcuate shoe arranged

for attachment on the hand wheel and formed
with an outward tapered surface sloping out-
wards from the front to the rear, a bottom
5 tapered surface sloping outwards from the
bottom up and meeting said tapered sur-
face, a vertical groove to the rear of the
tapered surfaces, and a stop member at-
10 tached on the shoe to the rear of the vertical
groove, and a vertical rod arranged to move
upwards against said tapered surfaces and
to finally engage in the vertical groove for
stopping rotation of the hand wheel.

In testimony whereof I have affixed my
signature.

15 SAMUEL KOCH.
